11 John P. Karns,

INVENTOR.

UNITED STATES PATENT OFFICE.

JOHN PRUE KARNS, OF BOULDER, COLORADO, ASSIGNOR TO THE J. P. KARNS TUNNELING MACHINE CO., OF BOULDER, COLORADO.

SPECIFICATION DETAIL.

No. 874,848.

Specification of Letters Patent.

Patented Dec. 24, 1907.

Application filed March 15, 1907. Serial No. 362,532.

To all whom it may concern:

Be it known that I, JOHN PRUE KARNS, a citizen of the United States, residing at Boulder, in the county of Boulder and State 5 of Colorado, have invented a new and useful Sink-Shaft Drill, of which the following is a specification.

This invention relates to drills, and has for its principal object to provide a drilling device 10 vice of simple construction for sinking vertical shafts and wells of large diameter and of such construction as will permit the rapid cutting without the aid of the percussive or forcing mechanisms universally employed in 15 drilling or tunneling machines of large diameter.

A further object of the invention is to provide an improved guiding means for maintaining the drill in vertical position while at 20 work.

A still further object of the invention is to provide a device of this class in which a sand pump may be used continuously, or practically so, and operated without stopping the drilling operation and without danger of damage to the pump.

With these and other objects in view, as will more fully hereinafter appear, the invention consists in certain novel features of 30 construction and arrangement of parts, hereinafter fully described, illustrated in the accompanying drawings, and particularly pointed out in the appended claims, it being understood that various changes in the form, 35 proportions, size and minor details of the structure may be made without departing from the spirit or sacrificing any of the advantages of the invention.

In the accompanying drawings:—Figure 1 40 is an elevation of a shaft sinking drill constructed in accordance with the invention, parts being broken away in order to more clearly illustrate the construction. Fig. 2 is a partial plan view of the same.

Similar numerals of reference are employed to indicate corresponding parts throughout the several figures of the drawings.

The drill head 10 is provided on its lower 50 face with a number of drill bits or cutters 11, these being preferably arranged so as to cover a large proportion of the lower surface of the drill head. A number of the drills are projected beyond the periphery of the head 55 proper and are provided with dove tailed

shanks 15 that are arranged to fit in correspondingly shaped grooves formed in lugs 16 that project from the periphery of the drill head.

Secured to or formed integral with the upper portion of the drill head are a number of spaced spokes or webs 18 which may be formed integral with a shaft 19, the latter being provided with an attaching device, such as an eye 20 for the reception of an operating cable, chain, or the like, by which the drill is raised while at work. Secured to the extended webs 18 is an annular casing or flange 21 which preferably extends some distance above the eye 20, and to the upper portion of this casing or flange are secured a number of guiding devices.

Each of the guiding devices in the present instance comprises a pair of plates 23 having pivot lugs 24 between which are mounted anti-friction rollers 25 for engagement with the vertical walls of the shaft. The plates 23 are guided by bolts 26, said bolts extending through suitable openings formed in the casing and plates, and surrounding these bolts are compression springs 27 that tend normally to maintain the anti-friction rollers in contact with the wall of the shaft.

The drill as a whole is made of such weight that it is merely necessary to raise and then drop the same, so that in falling by gravity the bits will cut away the rock or other material, and the latter when intermingled with water may be removed from the shaft by a sand pump or other suitable device.

It will be noted that the casing or vertical flange 21 of the drill head is of large diameter extending nearly to the wall of the shaft, and that the connecting eye 20 of shaft 19 is in a horizontal plane below the top of such casing. This construction permits the convenient introduction of the barrel of a sand pump during the operation of the drill, so that the water and heavy material at or adjacent to the bottom of the well or shaft may be removed without the necessity of removing the entire drilling mechanism as must ordinarily be done in the sinking of oil wells and the like.

It will be observed that the drill head is open so that the material disintegrated by the action of the drills will readily pass through the drill head to the interior of the flange or casing 21, in position to be removed by the sand pipe or other device. This con- 105 110

struction furthermore allows the drills to fall with great force into contact with the bottom of the well, the drill passing freely through the debris at the bottom of the well.

5. The sand pump barrel used is of the ordinary construction, *i. e.*, conical at both ends, and in descending the shaft, the body of the barrel may remain in engagement with the vertical wall, but its pointed lower end will 10 be within the vertical line of the casing, so that it will be guided into such casing and all danger of breakage from jamming between the shaft and drill will be avoided. This construction permits the introduction and operation of the sand pump at any time without the necessity of removing or even stopping the operation of the drill.

I claim:—

1. A percussive drilling mechanism for sinking shafts of large diameter, comprising an open drill head, a flange extending upward from the drill head and of less diameter than the latter, said flange forming a casing into which the material disintegrated by the 20 action of the drills and the water may pass, said flange forming a sand pump guide.
2. A percussive drilling mechanism for sinking shafts of large diameter, comprising a drill carrying head open for the passage of 30 water and other material, a casing extending upward from the drill head and into which such material may pass, a drill head carrying shaft, and connecting webs extending from the shaft to the casing.
3. A percussive drilling mechanism for sinking shafts of large diameter, comprising a drilling head open for the passage of water and other material, an annular flange extending upward from the head and forming 35 a casing into which such material will pass, a shaft carrying the drill head, webs connecting the shaft to the casing, and spring

mounted guiding rollers carried by the upper portion of said flange and arranged to engage with the wall of the shaft being drilled.

4. In drilling mechanism for sinking shafts of large diameter, an open drill head having a vertically extended casing open at the top, a shaft, a plurality of ribs extending from the shaft to the casing, and a series of spring 50 pressed anti-friction rollers carried by said casing and arranged to engage the wall of the shaft at a point above the drill head.

5. In percussive drilling mechanism for sinking shafts of large diameter, a drill head 55 arranged to carry a plurality of cutting bits at its lower face, said drill head being open to permit the free passage of water and other material, and an upwardly extending open flange carried by the drill head and of less 60 diameter than the latter, the flange forming a sand pump guide.

6. In drilling mechanism for sinking shafts of large diameter, a drill head open for the 65 passage of water and other material and having an upwardly extended flange or casing of less diameter than the drill head and forming a sand pump guide.

7. In percussive drilling mechanism for sinking shafts of large diameter, a drill head 70 open for the passage of water and other material and having an upwardly extended flange or casing forming a sand pump guide the flange being of less diameter than the drill head, and a drill head carrying shaft, the 75 top of which is in a plane below the top of said flange or casing.

In testimony that I claim the foregoing as my own, I have hereto affixed my signature in the presence of two witnesses.

JOHN PRUE KARNS.
